Ex

OR D 13,358

UNITED STATES PATENT OFFICE.

DICKSON R. LOWDEN, OF PHILADELPHIA, PENNSYLVANIA.

DESIGN FOR AN OIL-LAMP, &c.

SPECIFICATION forming part of Design No. 13,358, dated October 24, 1882.

Application filed March 30, 1882. Term of patent 7 years.

To all whom it may concern:

Be it known that I, DICKSON R. LOWDEN, a subject of the Dominion of Canada, residing at Philadelphia, in the county of Philadelphia and State of Pennsylvania, have invented and produced a new and original Design for an Oil-Lamp or Arm of a Chandelier, of which the following is a specification, reference being had to the accompanying photographic illustration, forming part thereof.

The photograph is a perspective view of the arm B, in combination with the oil-reservoir A and wick-chamber C. The arm has a middle and main part, *a*, of tapered form, connected with the ends *b* *c*. The reservoir A has a struck-up end, *d*, which is connected with the end *b* by means of the neck *e* and braces *f* and *f'*, and the end *c* is connected with the wick-chamber

C by means of the brace *g* and ornamental support *h*.

20

I claim—

1. The design for the tapered arm *B*, connected with the reservoir *A* by means of the ends *b* and *d*, the neck *e*, and braces *f* and *f'*.

2. The design of the tapered arm *B*, connected with the wick-chamber *C* by means of the brace *g* and ornamental support *h*.

3. The design for an arm of an oil-lamp or chandelier-lamp, consisting of the tapered part *a*, struck-up ends *b* *c*, the neck *e*, and braces *f*, *f'*, and *g*, and ornamental support *h*.

DICKSON R. LOWDEN.
